UNITED STATES PATENT OFFICE.

WILLIAM SOLOMON, OF CHEYENNE, WYOMING.

REACTION PROPELLING MECHANISM.

971,699.

Specification of Letters Patent.

Patented Oct. 4, 1910.

Application filed February 1, 1910. Serial No. 541,309.

To all whom it may concern:

Be it known that I, WILLIAM SOLOMON, a citizen of the United States, residing at Cheyenne, in the county of Laramie, State 5 of Wyoming, have invented certain new and useful Improvements in Reaction Propelling Mechanisms; and I do hereby declare the following to be a full, clear, and exact description of the invention, such as will enable others skilled in the art to which it 10 appertains to make and use the same.

This invention relates to ships and has special reference to a mechanism for propelling ships through the water.

15 One object of the invention is to improve the construction of reaction propelling mechanism so that the reaction impulses will take place successively.

With the above and other objects in view 20 as will be hereinafter apparent, the invention consists in general of a ship provided with a reaction impulse propelling mechanism of novel character.

The invention further consists in certain 25 novel details of construction and combinations of parts hereinafter fully described, illustrated in the accompanying drawings, and specifically set forth in the claim.

In the accompanying drawings, like characters of reference indicate like parts in the 30 several views, and:

Figure 1 is a side elevation of a ship constructed in accordance with this invention. Fig. 2 is a horizontal section showing the 35 mechanism, the section being taken on the line 2—2 of Fig. 1. Fig. 3 is an enlarged stern view of such a ship. Fig. 4 is a vertical longitudinal section on the line 4—4 of Fig. 2. Fig. 5 is an enlarged detail view 40 of the valve arrangement.

The numeral 10 indicates the hull of the ship and in this hull is located a driving engine 11 which may be either steam or gasolene although in the present instance it 45 is intended to represent a gasolene engine. This engine is operatively connected by a rod 12 with the piston rod of an air compressor 13 which supplies air to the storage tank 14. From this storage tank lead 50 delivery pipes 15, the pipes being close together where they leave the storage tank

and having their after ends connected with impulse tubes 16 which terminate outward beneath the counter of the ship and slightly forward of the rudder as clearly indicated 55 in Fig. 1. In each of the pipes 15 there is provided an ordinary valve 17, the two valves being alined and carried by a common stem 18 whereon is located a belt pulley 19. The shaft of the engine 11 is likewise 60 provided with a belt pulley 20 and a belt 21 connects these two belt pulleys.

It is obvious that a moving column of water impinging on the water at the stern of the vessel is more effective than a similar 65 column of air, this being due to the fact that the air column has a greater tendency to break up and rise to the surface. With the present invention the air is compressed by means of the engine and air compressor in 70 the tank 14. Now, as the engine runs to cause this compression the valves 17 are alternately opened by the rotation of the stem 18, this being caused by the belt and pulley arrangement. It will be plain from 75 this that the tubes 16 alternately have the water ejected therefrom by the inflowing air, the latter being prevented from dispersing and rising during the time of ejection by the confining action of the impulse 80 tubes. By reason of the alternate operation of these tubes, the tube which is not receiving a charge of air is being again filled with inflowing water, this water serving to expel the charge of air previously received in the 85 tube so that when this tube is next charged with air a new column of water is projected therefrom. It will also be plain that if only one tube were to be employed the impulses would still be caused by the successive admission of fluid pressure impulses to this 90 tube. There has thus been provided a device of this character of high efficiency and novel construction.

Having thus described the invention, what 95 is claimed as new, is:

In a propelling device for vessels, an air reservoir, a plurality of reaction tubes, separate ducts leading from said reservoir each connected to one of said tubes, valves in said 100 ducts having their ports disposed at angles to each other, a common stem whereon all

of said valves are mounted whereby the
ducts will have the respective valves opened
and closed in succession, a prime motor, an
air compressor actuated by the prime motor,
5 and an operative connection between the
prime motor and valve stem to rotate said
stem as the engine operates.

In testimony whereof, I affix my signature,
in presence of two witnesses.

WILLIAM SOLOMON.
